MODULAR ELEMENT FOR USE IN A POWER SUPPLY OR THE LIKE

James P. Ettinger and Christian S. Otteson, Ridgefield,
Conn., assignors to Electric Regulator Corporation,
Norwalk, Conn., a corporation of New York

Filed Apr. 25, 1967, Ser. No. 6,836

Term of patent 14 years

(Cl. D26—15)

FIG. 1

FIG. 2

FIG. 3

FIG. 4

FIG. 5

FIG. 6

FIG. 7

FIG. 1 is a three-quarter perspective view of a modular element for use in a power supply or the like showing our ornamental design;

FIG. 2 is a front elevational view thereof;

FIG. 3 is a side elevational view thereof taken from the left hand side of FIG. 2;

FIG. 4 is an end elevational view thereof taken from the lower end of FIG. 2;

FIG. 5 is a side elevational view taken from the right hand side of FIG. 2;

FIG. 6 is a rear elevational view thereof; and

FIG. 7 is an end elevational view thereof taken from the upper end of FIG. 2.

The dominant portions of our design are those shown in solid lines.

We claim:

The ornamental design for a modular element for use in a power supply or the like, as shown and described.
